UNITED STATES PATENT OFFICE.

WILLIAM J. DAVIDSON, OF BIG SPRING, VIRGINIA.

PLOW.

SPECIFICATION forming part of Letters Patent No. 307,920, dated November 11, 1884.

Application filed February 20, 1884. (No model.)

To all whom it may concern:

Be it known that I, WM. J. DAVIDSON, a citizen of the United States, and a resident of Big Spring, in the county of Montgomery and 5 State of Virginia, have invented certain new and useful Improvements in Plows, of which the following is a specification.

My invention relates to plows and cultivators, and has for its object to lessen the danger 10 of breaking, better adapt the plow to hold its proper course and facilitate its manipulation; and to these ends my invention consists in providing means whereby to permit the beam to rise or the mold-board to yield when the 15 latter is brought against a fixed object or is caused to penetrate soil of unusual hardness or density.

In the drawings, Figure 1 illustrates my invention in connection with a plow. Fig. 2 20 shows the same in connection with a cultivator. Fig. 3 is an enlarged section of part of Fig. 2.

To the beam A is pivoted the usual handles, C C, and the standard B may extend through 25 the beam, as in Fig. 1, and terminate in a screw-bolt, b, having the usual nut, d, and washer e. Beneath the washer is a spring or a block or pad of rubber, felt, or other yielding material, which is compressed by turning 30 the nut upon the bolt. The mold-board and landside are secured to the standard, and the lower ends of the handles are secured at the rear of the mold-board, so as to brace the latter, the standard, plow-blade and handles always in this case maintaining their relative 35 position, but the beam being capable of rising, swinging on its pivot and compressing the spring D. If the plow meets with any unusual obstruction, the plow-blade will be retarded or 40 arrested, but the beam will rise to a greater or less degree, thereby lessening the shock to the plow, horse, and driver, and preventing injury to the plow. This arrangement will also prevent the plow from jumping or rising from 45 hard ground. To still further reduce the shocks and facilitate the rising of the beam, a pad or spring, U, is introduced between the beam and nut at the point where the beam is pivoted to the handles, thereby permitting a slight 50 yielding of the connection at this point.

In Fig. 2 the invention is illustrated in con-

nexion with a plow-cultivator where the forked standard B is pivotally secured to the beam by a transverse bolt, a, so as to swing thereon, and a cross-bar, f, connecting the bars of the 55 standard, bears on a block or plate, g, between which and the beam is confined a block, D, of rubber or other elastic material, which permits a slight play of the beam in respect to the standard under circumstances before mentioned. The block g is of a wedge shape, as shown in Fig. 3, so that by driving it in, the rubber may be compressed, and is ribbed so as to catch upon the bar f, which thus holds it in place. A bracket or block, s, upon the 60 beam at the rear of the standard serves as a back bearing for the latter to take the strain off the bolt or portion of the standard that extends through the beam and insure a free movement. Side lips or lugs, t, prevent lateral 70 motion of the standard, and a guard, u, on the beam prevents grass, &c., from getting between the shoulder of the standard and under side of the beam.

I claim—

1. A plow provided with a beam capable of a limited motion in respect to the standard, and with a yielding or elastic substance or spring arranged above the beam, substantially as described.

2. The combination of the handles C, beam pivoted to the handles, standard extending through the beam, and spring D, compressed between the top of the beam and a bearing on the standard, substantially as described.

3. The combination of the handles, beam pivoted thereto, standard connected to permit the beam to move independently thereof, and spring between the two and spring U at the pivot of the beam, substantially as described.

4. The combination of the beam and standard connected to permit independent movement, the front guard, back bearing, and side lips, substantially as described.

In testimony whereof I have signed my name 95 to this specification in the presence of two subscribing witnesses.

WM. J. DAVIDSON.
